J. ROSENFIELD

GAME TOY

Filed Oct. 5, 1928

Jacob Rosenfield INVENTOR
BY Maurice Bloch
ATTORNEY

UNITED STATES PATENT OFFICE.

JACOB ROSENFIELD, OF BROOKLYN, NEW YORK, ASSIGNOR TO BAR-ZIM TOY MANUFACTURING CO. INC., OF NEW YORK, N. Y., A CORPORATION OF NEW YORK.

GAME TOY.

Application filed October 5, 1928. Serial No. 310,468.

This invention relates to improvements in game toys, and has for one of its objects the provision of a toy comprising a casing, a movable platform or hazard, and movable objects in simulation of airplanes, animals or the like adapted to land upon or enter the movable hazard when the toy is properly tilted, and the hazard is still in motion.

Another object of the invention is to provide a toy of the nature referred to of simple and inexpensive construction, and one that will amuse children as well as grown ups.

A further object of the invention is to provide a toy of this nature in which the entrances or landing portions of the movable hazard are painted in predetermined colors, and the movable objects are correspondingly colored, so that a player may by properly tilting the casing land the colored movable objects upon their correspondingly colored landings or in their respective entrances.

A still further object of the invention is to teach a player of the game to become expert in landing the movable objects in or upon their respective entrances or landings.

Further objects and advantages will become more apparent as the specification proceeds.

In the drawings forming a part of this specification

Figure 1 is a perspective view with parts broken away, showing one embodiment of my invention, and

Fig. 2 is a like view of a modified form of the invention.

Referring now to the drawings in detail 5 indicates a casing preferably made of thin sheet metal and provided at the sides and ends thereof with cardboard strips 6, between which strips and flanges 7 there is maintained a glass cover 8, and between which strips and bottom flanges 9 there is maintained a floor or base 10.

Within the casing 5 (Fig. 1) there is provided a hazard 11 mounted upon a ball bearing 12 so that the said hazard may move along the base 10 when the toy is tilted in any direction. The said hazard 11 may be provided at its ends with tapered platforms or landings 13 and 14 which may be colored red and blue respectively or any other colors that may be desired. Each of these platforms is provided with an indentation or recess 15. Movable objects 16 and 17 mounted

upon ball bearing 18, are also provided with in the casing 5. The said objects may be in the form of airplanes if desired and colored to correspond to the platforms 13 and 14 respectively. The indentations or recesses 15 provide seats for the balls 18 so that a plane 55 may be maintained upon the said platforms when once a player succeeds in landing a 60 plane thereon. By tilting the casing 5 and properly manipulating same a player is enabled to land the moving planes upon their 65 respectively colored platforms.

To play the game several players are each provided with a toy and the player who first succeeds in landing the planes on their respective platforms is declared the winner.

In Figure 2, I have shown a modified form of my invention in which instead of the plane carrier hazard, I provide a hazard in the form of a movable housing 20 mounted upon a ball 21 and provided with entrances 22 and 23. The immediate portions surrounding the said openings may each be suitably painted in a different color, and movable objects 24 and 25, painted in colors to correspond to the colors of the respective areas 70 surrounding the opening, are also provided within the casing. Each of the movable objects 24 and 25 may be provided with a ball 26 upon which they may easily roll when the toy is tilted to enable the said objects to 75 enter the housing through the proper opening therein.

From the above it will be seen that I have provided an amusing and interesting game 80 that can be played by both children and adults.

Many changes could be made in the above construction and many apparently widely different embodiments of this invention could be made without departing from the scope 95 thereof. It is intended that all matters contained herein in the above description or shown in the accompanying drawings shall be interpreted as illustrative and not in a limiting sense. It is also to be understood that the 100 language used in the following claims is merely intended to cover all the generic and specific features of the invention herein described, and that materials, sizes and relativeities of parts are non-essential, except as 105 called for in the claims.

If desired, the ball bearings hereinabove described may be omitted.

Having described my invention what I claim as new and desire to secure by Letters Patent is:

1. A toy of the nature described, comprising a casing, a base in the casing, a hazard adapted to move along the said base, and a movable object within the casing adapted to be received by hazard when the toy is tilted and the hazard is in motion.
- 10 2. A toy of the nature described comprising a casing, a base in the casing, a hazard adapted to move along the said base, a landing platform upon the hazard and a movable object within the casing adapted to ride up and seat itself upon the said platform when the toy is properly tilted and the hazard is in motion.
- 15 3. A toy of the nature described, comprising

ing a casing, a base in the casing and a plurality of movable objects within the casing adapted to move along the said base, some of the said movable objects being adapted to locate themselves in the remaining one of the said objects when the toy is tilted and the last mentioned object is in motion.

20 4. A toy of the nature described comprising a casing, a base in the casing, a hazard in the casing, adapted to move along the base thereof, a plurality of differently colored landing platforms on the hazard, and a like number of similarly colored movable objects within the casing, adapted to be rolled onto their respective similarly colored platforms when the toy is tilted and the hazard is in motion.

25 JACOB ROSENFIELD.
